PARACHUTE SUPPORTING DEVICE

Stig Ove Christian Kuhlemann and Carl Herman Lundholm, Stockholm, Sweden, assignors to Carl H. Lundholm, Aktiebolag, Stockholm, Sweden, a joint-stock company of Sweden

Application September 8, 1936, Serial No. 99,802
In Sweden September 20, 1935

7 Claims. (Cl. 244—151)

The present invention relates to supporting devices for parachutes. A number of supporting devices for parachutes are already known. In air forces of certain countries so called life belts with strap across the one shoulder are in use. In other countries again so called harnesses are employed. The harnesses may be provided with one or more straps running under the seat of the wearer and also with two straps extending 5 over the shoulders, so called shoulder straps, and finally with two straps fastened to the seat strap and running upwards between the legs of the wearer, so called leg straps. In an old type of harnesses the leg straps are fastened to straps running at the outside of the thighs by means of snap hooks, whereas the shoulder straps are held together with a waist strap by another snap hook.

In the last few years, however, harnesses have 20 come into use in which both the shoulder straps and the leg straps are held together by a single locking and release device. Hereby a rapid release from the harness is possible which is of great importance especially when landing in 25 strong wind or descent into water. In harnesses of this type the arrangement of the leg straps has proved to present the most difficult problem. According to one proposal the leg straps extend principally straightly from the seat strap 30 between the legs of the wearer to the central release device, which arrangement is very uncomfortable and may even present grave risks to the wearer in jumping. In order to remove this drawback the leg straps are according to 35 another proposal carried to the side by additional straps, which arrangement, no doubt, has been the best solution of this problem so far. In order to enable the leg straps to slide smoothly through the said additional straps it is, however, 40 necessary that the harness is under tension, which is mostly but not always the case during landing.

In order to effect a rapid release from the harness on landing, the same is provided with a 45 centrally placed locking and release device ("central release device") and in addition thereto with additional releasable locking devices ("side release devices") for holding the leg straps to the sides. The latter devices are actuated by special means from the central release device in such a manner that the same movement which causes release of the shoulder straps also causes release of the leg straps, the latter being preferably released a moment before 50 the shoulder straps.

The principal object of the present invention is to remove all the above said drawbacks and to provide a parachute supporting device or harness combining a rapid release of the wearer when landing or descending into water, with the 5 greatest possible comfort for the wearer while removing any risk of causing the wearer injury before and after the landing.

Another object of the invention is to provide a parachute supporting device having a 10 central release device and/or side release devices of new and useful design.

With regard to the central release device it has proved to be advantageous to provide same 15 with a slide or the like for the transmission of power therefrom to the side release devices for the actuation of the latter. This sliding means may be actuated by a leverage or a cog wheel device by means of which, on the actuation of the central release device, a pull is exerted in 20 wires or other members connecting said central device with the side release devices and adapted to actuate locking bolts or similar devices provided in the latter devices. Springs or the like may be provided to maintain said locking bolts 25 or similar devices in locking position.

The central release device may be actuated by a handle, knob or similar means which on the one hand is reliably secured in its position of rest, but on the other hand can be easily 30 grasped, even if the wearer has thick gloves on. For the actuation of the central release device it is also possible to make an outer casing thereof turnable, in which case, however, a releasable securing means must be provided.

For the engagement of the shoulder straps the central release device may be provided with pawls engaging snap hooks of said straps, or with locking pistons engaging openings in fittings provided at the ends of the shoulder straps. Also 40 the side release devices may be provided with locking pawls or claws, and they may be adapted to be provisionally fastened to any adjacent part of the supporting device, e. g. by means of snap hooks. It may be observed that snap 45 hooks used in combination with the central release device and/or the side release devices have the advantage that they may be released manually which is of importance, if for some reason or other such a device is destroyed, e. g. by a shot in war time.

It is of importance that the release of the different straps from the central release device and from the side release devices does not meet 50 too great a resistance, and that said release can 55

take place independent of the direction in which the manœuvring member of the devices is actuated. Of course, any unintentional actuation of said release devices must be impossible.

The invention can be applied to supporting devices of various kinds. Thus it can be used in combination with so called life belts provided with seat straps and leg straps, or with harnesses of the kind described above. The harnesses can either be fitted with shoulder straps which extend directly from the suspension straps supporting the parachute into the central release device or with shoulder straps fitted with branches to the central release device. In the last-mentioned harnesses the shock arising at the opening of the parachute is partially directed away from the central release device, whereby the latter need not have so high strength and may also be of smaller weight. In addition thereto the latter harness construction has several other advantages, for instance greater comfort. Further the suspension straps during and after the jump are spaced the head of the wearer thereby eliminating the risk of injury. For these reasons such harnesses are very suitable especially for military purposes.

The invention is illustrated by way of example on the accompanying drawings:—

Fig. 1 is a view of a harness having a central release fastening device as well as the two leg strap release devices.

Fig. 2 is a plan view of an embodiment of a central release device.

Fig. 3 is a sectional view along the line 3—3 in Fig. 5.

Fig. 4 is a sectional view along the line 4—4 in Fig. 5.

Fig. 5 is a longitudinal sectional view of an embodiment of a side release device.

Fig. 6 is a plan view of this embodiment.

Figs. 7 and 8 are sectional views of further embodiments of a side release device.

According to Fig. 1 reference numerals 10 and 11 designate supporting straps for the parachute extending downwardly to form a strap 12 running under the seat of the wearer. 13 and 14 are shoulder straps having their ends for placement at the front of the wearer and adapted to extend over the shoulders of the wearer to the back of the wearer and thence downwardly to be fastened to the seat strap 12. Each of the shoulder straps 13 and 14 has an adjustable connection 15 and 16, respectively, with the corresponding supporting straps 10 and 11. At the ends of the shoulder straps which are placed at the front of the wearer said straps carry each a snap hook 17, 18 for the connection with a central release fastening device 19. 20 and 21 are thigh straps which in the embodiment shown are carried under the seat of the wearer and through loops 22 and 23 on the supporting straps 10, 11 behind the back of the wearer. At a suitable point intermediate the seat strap portion and the loops 22, 23 the thigh straps 20 and 21 carry each a fitting 24, 25, respectively, releasably connected to the side release device 26, 27, respectively. 28 and 29 are leg straps secured at their one end to the seat strap 12 and carrying at their other end a fitting 30, 31, respectively, to be permanently connected with the corresponding side release device 26 or 27. The side release devices 30 and 31 are each carried by a strap 32 and 33, respectively, which may be considered to be continuations of the leg straps and which at their free end may be permanently connected with the central release device 19. These

straps 32 and 33 serve as support for a wire 35 connecting the side release device with the central release device 19, said wire 35 being preferably protected by a flexible tube 36.

In the central release device shown in Figs. 2 to 4, inclusive, the means for locking the snap hooks 17, 18 of the shoulder straps 13, 14 (see Fig. 1) comprises a rotatable bolting member 51 mounted on a square part of a rotatable pin and having two pawls 53 and 54 each adapted to engage one of said snap hooks 17, 18. The snap hooks are inserted into openings 55 of the rim 56 and upper and lower plates 57 and 58 of a casing of the central release device (only one 14 of the shoulder straps and the appurtenant hook 18 being shown in Fig. 5). The bolt 51 is manipulated by a handle 60 turnably mounted on a cross pin 61 extending through the square part 52 from the position of rest shown in the drawings into a position mainly at right angle thereto suitable for the manipulation of the handle. The handle 60 is retained in its position of rest by means of a blade spring 62 engaging the upper surface of the handle 60 and mounted on a cross pin 63 journalled in two lugs 64 on the casing of the release device. In this position of rest the handle 60 locks the bolt 51 by a pin 66 thereon engaging an opening in the upper plate 57 of the casing and extending into a recess 68 in the bolt (see Fig. 4).

The means of the central release device for locking the wires 35 controlling the side release devices (see Fig. 1) comprises a sliding member 10 guided in tracks 71 and having bores 73 for the insertion of the wires 35 which are introduced into said bores 73 through openings 74 in a protecting plate 75. Pivoted to the slide 10 is a lever 76 pivoted to a lug 77 of the bolt 51.

The operation of the central release device will be explained later on.

The side release device according to Figs. 5 and 6 comprises an upper part 80 and a lower part 81 each provided with a claw 82 and 83, respectively, forming an opening for the insertion of the fitting 24 of Fig. 1 or any other type of fastening member. The lower part 81 is secured to a support, in this case the strap 32. The parts 80, 81 are pivotally connected to each other by means of a hinge joint 84. The lower part 81 is provided with an ear 85 which engages a corresponding opening in the upper part 80. A bolt 86 engages said ear 85 of the lower part 81 and a bore in the upper part 80 and is actuated by a spring 87 adapted to hold the bolt in a position in which the parts 80, 81 are locked. The bolt 86 is connected to the wire 35 provided with the protecting tube 36. A spring 88 serves to accelerate the opening of the claws 82, 83 when the parts 80, 81 are disconnected by the bolt 86 being actuated.

The side release device shown may also be actuated manually. For this purpose a plate 90 connected with the bolt 86 is slidably mounted in a recess 91 of the upper part 80, said plate having a depression 92 for the engagement of a finger.

According to Fig. 7 the side release device comprises a single part 95 having a hook-shaped end 96 and serving as holder for the bolt 86 which in its locked position engages a recess 97 at the outer free end of the hook 96, the fitting 24 according to Fig. 1 or other fastening member engaging said hook 96.

According to Fig. 8 the fitting 24 is adapted to be inserted into a ring 100 which is secured

to a member 101 slidably mounted in a casing 102. A spring-actuated bolt 103 slides in a groove 104 of the casing 102 and is adapted to engage an opening in the member 101 thereby locking 5 the ring 100 and, thus, the fitting 24 in position. A spring 105 serves to facilitate the disengagement of the member 101 from the casing 102.

The operation of the device is as follows:—

When the harness is to be put on, one puts the 10 arms first through the slings formed by the shoulder straps 13, 14. The parachute pack on the back of which the seat strap 12 is arranged is placed under the seat. The leg straps 28, 29 are carried upwards between the legs together with 15 straps 32, 33, central release device 19 and side release devices 26, 27. The snap hooks 17, 18 are introduced into the openings 55 of the central release device and fastened therein by the pawls 53, 54. The fittings 24, 25 are fastened to the side 20 release devices (claws 82, 83 in Figs. 5 and 6, claw 96 in Fig. 7 and ring 100 in Fig. 8). Through the various adjustable buckles the harness is then 25 properly adjusted.

On landing the handle 60 is grasped and folded 25 upwards so as to be released from the securing spring 62. Thereby the bolt 51 is also released from its engagement by the pin 66 of the handle. Then the handle 60 is turned in the direction of the arrow in Fig. 2. By this turning movement 30 the slide 70 is first moved upwards by the lever 76 which causes a pull in the wires 35 controlling the side release devices 26, 27 resulting in a release of said devices in the following manner. According 35 to the embodiment shown in Figs. 5 and 6 the pull in the wire 35 results in the bolt 86 releasing the parts 80, 81 of the side release device causing opening of the claws 82, 83 under the action of the spring 88 so that the corresponding fitting 24 or 25 is released. In the embodiment according 40 to Fig. 7 a pull in the wire 35 causes the bolt 86 to be disengaged from the recess 97 of the claw 96 causing likewise release of the fitting 24 or 25. In the embodiment shown in Fig. 8 a pull in the wire 35 causes the locking bolt 103 to release 45 the slide 101 which is disengaged from the casing 102 under the action of the spring 105 whereby the slide 101 is released together with the fitting 24 or 25 fastened to the ring 100.

Further turning movement of the handle 60 50 causes the snap hooks 17, 18 of the shoulder straps 13, 14 to be disengaged by the pawls 53 and 54, respectively, whereby said straps are released. The whole of the middle part of the harness is then released and falls forwards giving the wearer 55 freedom.

As described above the wires 35 are released a fraction of a second before the release of the shoulder straps. Thereby the advantage is attained that the wires are in tension when the 60 power is transmitted through them from the slide 70 of the central release device to the side release devices 26, 27 ensuring a reliable release of the latter.

In harnesses having branches from the suspension straps to the central release device, the wearer must, after the central lower portion of the harness has been made free, shake off the upper part of the harness. In harnesses in which the straps entering the central release device are 70 direct continuations of the supporting straps the wearer is made free at once from the harness. The latter type of harness, however, has the drawback that, when the parachutist hangs in the harness, the supporting straps come close to 75 his head which under unfavourable circumstances

can cause him injury, especially during the opening of the parachute.

In life belts arranged according to the invention the wearer is also free at once. Life belts, however, have the drawback that the greater part 5 of the opening shock is taken up by the stomach and the breast of wearer, which may cause him injury, especially at drops at high speeds.

Several variations of the invention are possible. Thus the central release device can be operated 10 by another movement than a turning one. Further the side release devices need not necessarily be of the constructions described.

Having now described our invention, what we claim as new and desire to secure by Letters 15 Patent is:

1. In a parachute supporting device, the combination of a body attaching strap having its ends for placement at the front of the wearer, a pair of leg straps, a separate device for each of said leg straps each comprising a locking member adapted releasably to connect the leg strap to part of the supporting device, a quick release fastening device releasably connecting together the ends of the body attaching strap which are placed at the front of the wearer, a slide in said quick release fastening device, wires connecting said slide with the locking members of the leg strap holding devices, and means in said quick release fastening device, whereby upon release of said device first the locking members of the leg straps holding devices are released and then the ends of the body attaching strap are disconnected so as to permit the wearer to free himself from the supporting device. 30

2. In a parachute supporting device, the combination of a body attaching strap having its ends for placement at the front of the wearer, a pair of leg straps, a separate device for each of said leg straps each comprising a locking member adapted 40 releasably to connect the leg strap to part of the supporting device, a quick release fastening device releasably connecting together the ends of the body attaching strap which are placed at the front of the wearer, a slide in said quick release fastening device, wires connecting said slide with the locking members of the leg strap holding devices, means to protect said wires, and means in said quick release fastening device, whereby upon release of said device first the locking members of the leg straps holding devices are released and then the ends of the body attaching strap are disconnected so as to permit the wearer to free himself from the supporting device. 45

3. In a parachute supporting device, the combination of a body attaching strap having its ends for placement at the front of the wearer, a pair of leg straps, a separate device for each of said leg straps comprising a locking member and adapted releasably to connect the leg strap to 60 part of the supporting device, a quick release fastening device releasably connecting the ends of the body attaching strap which are placed at the front of the wearer, and means controlled by said quick release fastening device to release 65 the locking members of the leg strap holding devices, whereby, upon release of the quick fastening device, the leg strap holding devices are released and the ends of the body attaching strap are disconnected so as to permit the wearer to 70 free himself from the supporting device said leg strap holding devices being adapted to remain in released position after having been released by the quick release fastening device. 75

4. In a parachute supporting device, the combi-

nation of a body attaching strap having its ends for placement at the front of the wearer, a pair of leg straps, a separate device for each of said leg straps adapted releasably to connect the leg strap to part of the supporting device, a quick release fastening device releasably connecting the ends of the body attaching strap which is placed at the front of the wearer, said leg strap holding devices comprising each a spring actuated locking member, a wire connecting each of said locking member with the quick release fastening device, and means in the latter to control said wires whereby, upon release of the quick release fastening device, the locking members of the leg strap holding devices are released by the wires and the ends of the body attaching strap are disconnected so as to permit the wearer to free himself from the supporting device, said leg strap holding devices being adapted to remain in released position after having been released by the quick release fastening device.

5. In a parachute supporting device, the combination of a body attaching strap, having its ends for placement at the front of the wearer, a pair of leg straps, a separate device for each of said leg straps adapted releasably to connect the leg strap to part of the supporting device, a quick release fastening device releasably connecting the ends of the body attaching straps which are placed at the front of the wearer, said leg strap holding devices comprising each a locking member and a spring adapted to keep said member in position to lock the leg strap holding device to said part of the supporting device, but to permit

said device to remain in released position, and means to connect said locking members to said quick release fastening device, whereby, upon release of the latter, the locking members are released and kept in released position and the ends 5 of the body attaching strap are disconnected, so as to permit the wearer to free himself from the supporting device.

6. A parachute supporting device comprising in combination a body engaging member including 10 shoulder straps and leg straps, a main release device situated at the front of the wearer and including means for releasably engaging the shoulder straps, other release devices releasably connecting the leg straps to portions of the body 15 engaging device and including releasable locking members operatively connected to the main release device, and actuating means in the main release device for first actuating the last mentioned release devices so as to release the leg 20 straps prior to and in timed relation with the release of the shoulder straps.

7. In a parachute harness including shoulder straps and leg straps, at least three release devices, two of which are associated with the leg 25 straps, the remaining release device being associated with the shoulder straps and operatively connected with the first mentioned release devices and including means whereby on operation the first mentioned release devices are operated to 30 release the leg straps immediately prior to the release of the shoulder straps.

STIG OVE CHRISTIAN KUHLEMANN.
CARL HERMAN LUNDHOLM.
